UNITED STATES PATENT OFFICE.

WALTER J. KNEE, OF OMAHA, NEBRASKA, ASSIGNOR TO UNDERWOOD TYPEWRITER COMPANY, OF NEW YORK, N. Y., A CORPORATION OF DELAWARE.

TYPEWRITING MACHINE.

Application filed August 11, 1925. Serial No. 49,511.

This invention relates to collating devices for typewriting machines, which are provided with means for holding work-sheets against the platen at the printing line.

Many concerns send statements every month, which consist of a few groups of figures, each group being typed in its particular column, and often all the groups are arranged in one line. A carbon-copy of several statements is usually made on one record-sheet. An object of this invention is the provision of a simple collating device for typewriters with which such statement-sheets can be prepared in a typewriter with a minimum of collating operations.

To this end, provision is made in the present invention of chutes, each having an interior width slightly greater than the statement-cards to be used in it. These chutes may be fastened, one at a time, to a cross-bar which may be detachably mounted on plates fast on U-shaped brackets slidably mounted on a stiff horizontal rod, the latter being held fast on the usual carriage-frame ends. The chutes are provided with a back wall and a front wall, the latter terminating a short distance above the printing line of the platen. A plurality of downwardly-extending, narrow, flexible curved fingers may be mounted on said front wall to coincide with and overlie column-dividing lines of the statement-cards. These fingers are arranged to hold the cards against the platen at the printing line thereof, and guide its leading edge between the platen and a paper-table apron. Characters may be typed between the narrow fingers. Work-sheet-holding rolls are provided on each side of each chute for holding a record-sheet on the platen. By using cards sufficiently stiff that fit their particular chutes correctly, the cards may be quickly inserted and gaged by the wing-scales to printing position with one movement, since they require gaging in vertical direction only. No further operation of any collating mechanism of the machine is required unless two or more lines are to be typed. In such cases the platen needs only to be line-spaced.

A feature of the invention is the arrangement of the lower ends of the narrow fingers to fit between broad teeth provided in the apron-extension of the usual paper-table, to prevent the cards from catching on the end of the apron when they are pushed down

around the platen. Another feature is the provision of simple means for mounting the card-holding fingers for lateral adjustment on the chute.

Other features and advantages will hereinafter appear.

In the accompanying drawings,

Figure 1 is a fragmentary front view of the present invention, embodied in an Underwood typewriting machine, and illustrates how a statement-card appears in the device.

Figure 2 is a fragmentary cross-sectional view of the device in Figure 1, and shows certain features of the typewriting machine which were omitted in Figure 1 for the sake of clearness.

Figure 3 is a perspective view of the chute of the present invention, arranged with adjustable work-sheet-holding fingers.

A type 10 held on a type-bar 11 is arranged as usual in an Underwood typewriting machine to be operated by keys, not shown, to strike against a platen 12 mounted on a shaft 13, which is journaled in carriage-frame ends 14. A ratchet-wheel 15 arranged for rotation, step by step, by the usual finger-piece, not shown, and two finger-wheels 16, one of which is shown, are mounted on shaft 13 for line-spacing the platen 12. Feed-rolls 17 and 17^a, shown in both operative and released positions, may be operated by the usual means, not shown. A usual paper-table 18, except for modifications of its front apron-extension 19, as will be hereinafter described, may be arranged in the rear of platen 12.

A stiff rod 20 is held fast by screws 21 in brackets 22, the latter being fastened by screws 23 to the carriage-frame ends 14. Rolls 24 and 25, arranged for pressing against the platen 12, are carried by flexible fingers 26 and 27, respectively, which are fastened by screws 28 to U-shaped brackets 29 and 30, respectively. The brackets are slidably mounted on rod 20, with a base or lateral portion 31^a of an L-shaped plate 31 fastened on the bracket 29, between it and the finger 26. A similar L-shaped plate 32 is fastened on a U-shaped bracket 34 adjacent the left end of the platen 12. The right end of a stiff bar 35, having a rectangular cross-section, may be fastened by a screw 36 to plate 31, and the left end of the bar, which is arranged with an open-end L-shaped slot 37, may be fastened by a screw

38 to plate 32, the slot 37 permitting the bar 35 to be quickly attached and detached. To hold the brackets 29 and 34 against undesired lateral or rotary movement on rod 5 20, hubs 45, provided with screws 46, may be soldered to the outer and shorter arms of the brackets. Bracket 30 may have a flat spring 30^a arranged to engage a groove, not shown, in the under side of the rod 20, 10 to hold the bracket against rotary movement around the rod while permitting easy lateral adjustment thereon.

A chute 50, positioned above the platen 12, between the rolls 24 and 25, which may 15 have converging and rearwardly-inclined front and back walls 51 and 52, respectively, is fastened on the bar 35 by screws 53, set in countersinks 54 of the back wall 52, so that the screw-heads do not project above 20 the front side of the back wall. The chute 50 may have ends made by riveting or soldering together flanges 57, 58 and flanges 59, 60 of the front and back walls, respectively.

25 To use the collating device, a record-sheet 61, with an overlying narrower carbon-sheet 62, may be inserted around the platen 12 from the rear in the usual way, being passed under the rolls 24 and 25, and up behind the 30 chute 50, and properly gaged by means of the usual wing-scales 72, whose top edges 73 may rest against the convex surfaces of the fingers 66. The feed-rolls 17 and 17^a may now be cast off, and a statement sheet or card 35 63, having ruled columns 64 with vertical dividing lines 65 and appropriate headings or designations for the columns, may be inserted in the top of the chute 50. To facilitate inserting and withdrawing the statement-card 63, the front and back walls 51 and 52 may have central top portions 51^a and 52^a, respectively, removed. The lower 40 edge of the front wall may be arranged approximately tangent to the platen, just above the printing line. To hold the statement-card 63 closely against the record and carbon sheets 61 and 62 on the platen 12, a plurality of curved flexible fingers 66 are provided which have a wide portion 67 for fastening 45 them along the lower edge of the front wall 51 by riveting or soldering. The lower portions 68 of the fingers 66 will preferably be very narrow and no thicker than necessary 50 to give sufficient strength for holding the statement-card 63 closely against the platen 12, since they extend down below the printing line and must clear the usual ribbon-vibrator, not shown. The pressure of the 55 fingers 66 and rolls 24 and 25 against the platen 12 can be varied by a small rotation of rod 20.

The statement-card 63 will preferably be printed on paper or cardboard slightly narrower than the inside width of the chute 50, 60 and will be sufficiently stiff to allow it to

be readily pushed between the platen and the flexible finger-portions 68 without buckling the card. Statement-cards will preferably be arranged for a particular chute 50 that they are to be used with, so that the column-dividing lines 65 will always come under the narrow finger-portion 68. Thus characters may be printed between the narrow finger-portions 68 across substantially the whole width of the columns 64.

To guard against the lower edge of the statement-card 63 catching on the top edge 69 of the apron 19 when the card is being inserted, the apron may have shallow teeth 70 arranged so that the lower ends of the 75 narrow finger-portions 68 may rest against the platen 12 in notches 71 between the teeth 70. Thus the lower edge of a card will be past the top end of apron 19 before it is 80 out from under the pressure of the fingers 66.

When the leading edge of the statement-card 63 has been pushed down past the printing line and the card has been gaged to printing position by the wing-scales 72, one line 90 of data may be typed at once. To type two or more lines, the platen 12 may be line-spaced by one of the finger-wheels 16, or by throwing on the feed-rolls and operating the usual line-spacing finger-piece, not shown. When all the desired data has been typed on a statement-card 63, the feed-rolls 17 and 17^a will be cast off, and the card 63 can be 95 easily pulled from the top of the chute without changing the position of the record-sheet 61, which is securely held by the pressure of the rolls 24 and 25.

To remove the chute 50 and replace it with one of a different width, the screw 36 may be removed and the screw 38 released, and the bar 35 carrying the chute 50 may then be removed. The screw 46 may next be released, and the bracket 29 carrying plate 31 may be moved to the new position and the screw tightened. The bar 35 carrying a different width chute may now be fastened on the plates 31 and 32. It can be readily seen that the collator can be easily and quickly removed from the typewriting machine by unscrewing the screws 21 and removing the collator upwardly.

In Figure 3 is illustrated how the card-holding fingers 166 may be arranged for lateral adjustment along the chute 50. A rectangular rod 175 may be fastened by screws 176 to flaps 177 integral with the front wall 51 and bent around in front of said wall. Each finger 166 may have a flattened portion 167 fastened by soldering or welding to a split rectangular ring 169 arranged for a sliding fit on the rod 175, and each ring may have a screw 170 for holding it in position on the rod.

The chute 50 can be simply and inexpensively made, and a separate chute for each 130

- different kind of statement-card used in an office may be provided at a small cost. By having a card arranged to fit the chute permits easier and faster insertion of the card, 5 since no lateral gaging will be needed. In cases where only one line is required to be typed on a statement-card, the card can be quickly inserted in the chute and pushed down to the proper printing position ready 10 to be typed without any other collating operation. After it is typed and withdrawn, the record-sheet may be line-spaced one line with a finger-wheel 16 and the next card inserted in like manner.
- 15 Variations may be resorted to within the scope of the invention, and portions of the improvements may be used without others. Having thus described my invention, I claim:
- 20 1. The combination with a typewriting machine having a platen and a carriage-frame, of a rod above and parallel to said platen and fast in said carriage-frame, a chute detachably mounted on said rod and 25 arranged for guiding statement-sheets provided with vertical column-lines against said platen, record-sheet-holding rolls engaging against said platen and adjustably mounted on said rod, one roll being on each side of said chute, a plurality of narrow downwardly-extending fingers fastened on said chute and positioned to coincide with and overlie the vertical column-lines on said statement-sheets and arranged for holding said statement-sheets closely against said platen, so 30 that characters may be typed thereon between said fingers, and a paper-table apron provided with wide short teeth extending upwardly between said fingers.
- 35 2. In a typewriting machine, the combination with a platen, of a chute arranged for guiding a work-sheet tangentially against said platen a short distance above the printing line, and a plurality of narrow flexible curved fingers fastened to said chute and extending downwardly therefrom and arranged to hold said work-sheet with adjustable pressure against said platen at the printing line thereof, whereby characters 40 may be typed on said work-sheet between said fingers.
- 45 3. In a typewriting machine, the combination with a platen and a paper-table apron, of a chute having a front wall and a back wall arranged for guiding a work-sheet against said platen above the printing line, and a plurality of narrow curved fingers fastened to the lower portions of said front wall and extending downwardly therefrom between teeth in the top of said apron, said fingers being arranged to hold said work-sheet against said platen at the printing line thereof.
- 50 4. The combination with a typewriting machine having a platen and a carriage-frame, of a rod supported on said frame parallel to and above said platen, two brackets mounted on said rod, each bracket having an upwardly-extending plate-member and being positioned adjacent each end of 55 said platen, a rectangular rod detachably mounted on said plate-members and parallel with said platen, a chute mounted on said rectangular rod arranged for guiding statement-sheets against said platen above the printing line, narrow convex flexible fingers fastened to the lower portion of said platen and arranged for holding the statement-sheets against said platen at the printing line thereof, and two statement-sheet-holding rolls engaging said platen and mounted on said frame-supported rod, one roll being positioned on each side of said chute.
- 60 5. The combination with a typewriting machine having a platen, of a chute arranged for guiding a work-sheet provided with column-dividing lines against said platen below the printing line thereof, and a plurality of narrow curved fingers fastened to the lower portion of said chute and extending downwardly therefrom, said fingers being arranged to hold said work-sheet against said platen and being positioned so as to coincide with and overlie said column-dividing lines.
- 65 6. The combination with a typewriting machine having a platen and a paper-table apron, of a chute arranged for guiding a work-sheet having vertical column-dividing lines against said platen above the printing line thereof, and a plurality of narrow curved downwardly-extending fingers fastened to the lower portion of said chute and arranged to hold said work-sheet against said platen, each of said narrow fingers being positioned so as to coincide with and overlie one of said column-dividing lines and to extend below the upper end of said apron.
- 70 7. The combination with a typewriting machine having a platen and wing-scales, of a chute arranged for guiding a work-sheet against said platen, a plurality of narrow convex fingers fastened to said chute and extending downwardly therefrom, said fingers being arranged to hold said work-sheet against said platen at the printing line thereof, said chute having a slightly greater interior width than said work-sheet, whereby the sides of the chute may serve as lateral gages, and the upper edges of said wing-scales serving as a vertical gage.
- 75 8. The combination with a typewriting machine having a platen, of a chute having a front wall and a back wall arranged for guiding work-sheets against said platen, a plurality of narrow curved fingers fastened to the lower portion of said front wall for guiding said work-sheets around said platen below said chute and an apron-extension of a paper-table, said extension being formed

- with wide short teeth which are arranged between the lower ends of said fingers, the ends of the fingers and the teeth being in substantially the same curved plane.
- 5 9. The combination with a typewriting machine having a platen, of a chute having a front wall and a back wall arranged for guiding work-sheets against said platen, a plurality of narrow flexible convex fingers 10 fastened to the lower portion of said front wall and arranged to lie against said platen with a light pressure, and means for varying the pressure of said fingers against said platen.
- 15 10. The combination with a typewriting machine having a platen and a carriage-frame, of a rod parallel to said platen and held on said frame by screws, two brackets mounted on said rod and arranged for angular adjustment about the same, a chute having a front wall and a back wall supported on said brackets and arranged for guiding a work-sheet against said platen, and a plurality of narrow flexible convex 25 fingers arranged to press lightly against said platen and below said chute for holding work-sheets against the platen at the printing line thereof, said fingers being attached to the bottom portion of said front wall, whereby the pressure against the platen may be varied by angular movement 30 of said brackets about said rod.
11. The combination with a typewriting machine having a platen and a carriage-frame, of a rod above and parallel to said platen and fast on said frame, two brackets adjustably mounted on said rod, each bracket having an upwardly-extending plate-member and being positioned adjacent each end 35 of said platen, a rectangular rod detachably mounted on said plate-members, a third U-shaped bracket slidably mounted on said carriage-frame rod and normally positioned between said two adjustably mounted brack- 40 ets near the left one, two rolls engaging against said platen for holding a record-sheet on the same, one of said rolls being fastened by flexible fingers to the right-hand bracket, and the other being fastened in like manner to the middle bracket, a chute 50 mounted on said rectangular rod between said rolls and arranged for guiding a statement-sheet against said platen, and a plurality of narrow curved downwardly-extending fingers fastened on said chute and arranged for holding said statement-sheet against said platen at the printing line thereof.
- 55 12. In a typewriting machine, the combination with a platen and a carriage-frame, of a chute mounted on said carriage-frame above the printing line of said platen and arranged to guide work-sheets having vertical column-lines against said platen, and a plurality of narrow convex fingers fastened on said chute and positioned to coincide with and overlie said column-lines, said fingers being arranged for holding said work-sheets against said platen at the printing line thereof and being mounted for lateral adjustment along said chute.
- 60 13. In a typewriting machine, the combination with a platen, a paper-table apron and a carriage-frame, of a chute mounted on said carriage-frame above the printing line 65 of said platen and arranged to guide work-sheets having vertical column-lines against said platen, a square rod fastened to said chute a short distance in front of the same and arranged parallel to said platen, and a plurality of narrow curved fingers slidably mounted on said rod and fastened over said column-lines and arranged for holding said work-sheets closely against said platen at the printing line and guiding said work-sheets between said platen and said apron.
